M. L. BRAINARD.
EGG CARRYING CASE.
APPLICATION FILED AUG. 20, 1912.

1,057,407.

Patented Apr. 1, 1913.

UNITED STATES PATENT OFFICE.

MORELL L. BRAINARD, OF BELFAST, NEW YORK, ASSIGNOR TO MAUDE E. SULLIVAN,
OF ROCHESTER, NEW YORK.

EGG-CARRYING CASE.

1,057,407.

Specification of Letters Patent. Patented Apr. 1, 1913.

Application filed August 20, 1912. Serial No. 715,980.

To all whom it may concern:

Be it known that I, MORELL L. BRAINARD, residing at Belfast, in the county of Allegany and State of New York, have 5 invented certain new and useful Improvements in Egg-Carrying Cases, of which the following is a specification.

This invention relates to packing cases for the convenient carrying and handling 10 of eggs, and my said invention more especially has reference to the peculiar and novel construction of a cover or lid for carriers of the character stated, and the means for fastening the said cover to the case or 15 box.

My invention has for its object to provide an improved egg case cover and fastening means therefor of a simple and economical construction in which much time and expense is saved in putting on and holding 20 the cover on the case.

With other objects in view, that will hereinafter appear, this invention consists in the novel arrangement and peculiar combination of parts hereinafter explained, 25 specifically pointed out in the appended claim and illustrated in the accompanying drawing, in which:—

Figure 1, is a perspective view of an 30 egg carrying case, embodying my improvements. Fig. 2, is a longitudinal section of the same, the top member being shown as swung back and held in the upright position in full lines. Fig. 3, is a similar view 35 of the upper part of the case or carrier, the cover being shown down to the locked position. Fig. 4, is a perspective view of one end of the box or case, one of the cleats being shown removed to the more clearly 40 illustrate one of the swinging or supporting links hereinafter referred to.

In the practical application of my invention, and as embodied in an egg carrying case, the case or box body 1 has the usual 45 rectangular shape, and is formed of the opposite end boards 10-10, and the side boards 11-11, the said end boards being fitted between the side boards so that the ends of the latter extend beyond the ends 50 to provide for flush fitting of the upper and lower cross cleats 2 and 3 that act as reinforcing means for the box ends, the upper cleats having an additional function, presently explained, the lower cleat 3 at one

end also serving as a rest or supporting 55 member, as will presently also appear.

In the practical use of my box for carrying eggs, the latter are packed in compartments, as indicated in Fig. 2. The top or cover 4 is a plain board having the rectangular shape of and the full length and width of the said box and having cross cleats 45-46 on its under side. At one end, the top 4 has a simple transverse groove 41 and at the other end a similar groove 42 65 having an undercut edge 43. At that end of the cover having the groove with the undercut edge is secured a wire bail 5 formed of a wire strand bent into a rectangular shape whereby to provide parallel 70 members 51-52 one of which 51 seats against the outer edge of the adjacent box end and has its ends fulcrumed in notches 53 cut in the ends of the opposite side pieces of the box, and is held to its seat by the 75 upper cleat 2, nailed or clenched to the said box end. The bail 5 is of such width that in swinging it up over the box top or cover, its member 52 can be sprung into and interlocked with the under cut groove 42. 80

6 designates a swinging bail also of rectangular shape, one member of which seats against the outer upper end of the contiguous end of the box, the side boards at that end having notches 60 to receive the said 85 bail member, which latter is secured to its seat by the upper box cleat 2 at that end. The other member 61 of the said bail 6, is rockably mounted in the groove 41 in the box top and is securely held in the said 90 groove by staples 62.

By reason of the peculiar construction and arrangement of the parts, as described, when packing the case, the cover can be quickly raised by releasing the bail 5 and 95 swinging it back, (see Fig 2) to release that end of the cover, and when thus released, the cover can be swung up off the casing top and turned to the vertical position, over the end of the box to which it is secured, 100 with its cross cleat 46 resting on the lower cross cleat 3 at that end of the box, the bail 6 now serving to sustain the said cover in its upright position and from accidental displacement from that position. 105

In closing the box or casing, the cover is swung down and forwardly with its cross cleat 45 adjacent the inner edge of that end

of the box that has the bail 5 and when thus closed by swinging the bail over to engage the undercut groove, the said bail locks itself in the said groove and by reason of its 5 spring it draws the cleat 45 of the cover tightly against the said end of the box.

What I claim is:

A carrying case, comprising a rectangular open top box, the sides of which extend beyond the ends, the extensions of the sides having opposing notches, rectangular bails formed of spring wire, one for each end of the box, one member of each of the said bails fitting the notches at their respective ends of the box, reinforcing cleats secured at the ends of the box over the bail portions that pass over such ends, a cover having a transverse groove in each end of

the top thereof, one of the grooves having an undercut edge whereby the free end of the bail at that end of the box can be sprung into and interlocked with the said undercut groove, the bail at the other end of the box having its free end rockably held in the groove in the cover at that end, the said end 25 of the box including a lower transverse cleat, and the cover of the box having a cleat on its under side adapted to rest upon the said lower transverse box cleat when the said cover is swung to its open upright position 30 over the end of the box.

MORELL L. BRAINARD.
